UNITED STATES PATENT OFFICE.

SYDNEY K. WILSON, OF PHILADELPHIA, PENNSYLVANIA.

CONDENSER.

Application filed January 26, 1925. Serial No. 4,883.

This invention relates to a condenser for use in radio receiving sets, and an object of the invention is to provide a condenser in which a stationary and a movable cylinder are utilized, the movable cylinder being mounted for telescoping within the stationary cylinder for varying the capacity of the condenser, thereby providing a condenser which has practically a straight line effect from minimum to maximum capacity and vice versa, and one which will allow the calibrating of wave length on any type of radio receiving structure.

A further object of the invention is to provide in a condenser as specified, a movable cylinder which is moved relative to the stationary cylinder by means of a threadable connection with a shaft, thereby permitting extreme delicacy and accuracy in the adjustment of the cylinders for regulating the capacity of the condenser and also providing a vernier condenser from maximum to minimum capacity, the accuracy of adjustment being controlled by the number of threads per inch on the threaded feeding shaft.

A further object of the invention is to provide a condenser as specified in which "body capacity" and the resulting undesirable noises and inaccuracy in the receiving set will be eliminated.

Other objects of the invention will appear in the following detail description, and in the accompanying drawings wherein:

Figure 1—is a longitudinal section through the condenser.

Figure 2—is a cross section through the condenser.

Figure 3—is a detail longitudinal section through the feeding sleeve.

Referring more particularly to the drawings, the improved condenser comprising a front plate 1 and a back plate 2 which plates are made of any suitable insulating material, such as "bakelite" or the like. The front and back plates 1 and 2 are connected by suitable clamping rods 3 which also serve as guide rods for the spider structure 4. The spider structure 4 has a plurality of guiding bearings 5 formed on the arms 6 thereof, while a metal cylinder 7 of aluminum, brass or any other suitable material is carried by the perimeter of the spider structure. The cylinder 7 forms one of the adjustable plates which control the capacity of the condenser while the stationary cylinder

8 forms the other of the co-operating members. The cylinder 8 is also formed of aluminum, brass or other suitable metal, and it is carried by the back plate 2 and is of slightly larger internal diameter than the external diameter of the movable or adjustable cylinder 7.

In the drawings, a cylinder 9, of glass or any other suitable dielectric material is illustrated, which is placed between the inner and outer surfaces respectively, of the cylinders 8 and 7. The hub 10 of the spider 4 is internally screw threaded and the threads co-act with the threads 11 on a metal sleeve 12 which has its smooth end 13 mounted in a suitable bearing 14 in the back plate 2. The sleeve 12 is mounted upon a shaft 15 which is made of any suitable insulating material, such as "bakelite" or the like, and it is pinned thereon by means of a pin 16. A spring 17 engages the pin 16 and the bearing 14 for holding the sleeve in position. The shaft 15 projects outwardly through the front plate 1 and is adapted to project through the panel indicated at "A" of a radio set, and have a dial or knob "B" of approved construction on its outer end to facilitate rotation of the shaft 15 and sleeve 12 for moving the spider 4 and consequently the cylinder 7, inwardly into or outwardly out of the cylinder 8. One of the guiding rods 3 has a binding post 18 thereon to permit one connection with the condenser while the other connection may be made through a binding post 19 to the cylinder 8 or the wire may be soldered or otherwise suitably attached to the cylinder.

While in the foregoing description and in the accompanying drawings the improved condenser has been illustrated with only a single movable and a single stationary cylinder, it is to be understood that a plurality of movable and stationary cylinders may be provided if it is found necessary to do so, without departing from the spirit of this invention.

It is, of course, to be understood, that the invention may be constructed in various other manners and the parts associated in different relations, and therefore, I do not desire to be limited in any manner, except as set forth in the claims hereunto appended.

What I claim is:

1. In a condenser for radio receiving structures, a front and back plate, a cylinder of dielectric material between said front

and back plates, a stationary metal cylinder surrounding substantially one-half of said dielectric cylinder, and a movable metal cylinder within the dielectric cylinder for movement into or out of the stationary metal cylinder.

2. In a condenser for radio receiving structures, a front and back plate, a cylinder of dielectric material between said front and back plates, a stationary metal cylinder surrounding substantially one-half of said dielectric cylinder, a movable metal cylinder within the dielectric cylinder for movement into or out of the stationary metal cylinder, a shaft of insulating material, and a feed screw carried by said shaft, and means connecting said feed screw and movable cylinder.

3. In a condenser for radio receiving apparatus, a front and back plate, a cylinder of dielectric material, of said plates, a stationary metal cylinder surrounding substantially one-half of said dielectric cylinder, a movable metal cylinder within said

dielectric cylinder for movement into or out of said stationary metal cylinder, and guide rods carried by said front and back plates for guiding movement of said movable cylinder.

4. In a condenser for radio receiving apparatus, a front and back plate, a cylinder of dielectric material, of said plates, a stationary metal cylinder surrounding substantially one-half of said dielectric cylinder, a movable metal cylinder within said dielectric cylinder for movement into or out of said stationary metal cylinder, a shaft of insulating material, a threaded sleeve mounted upon and rotatable with said shaft, said threaded sleeve connected to said movable metal cylinder for fitting the movable metal cylinder, and guide rods carried by said front and back plate for guiding movement of said movable cylinder.

In testimony whereof I affix my signature.

SYDNEY K. WILSON.
